DOLL

Benjamin Kinberg, New York, N. Y.

Application August 4, 1950, Serial No. 177,599

3 Claims. (Cl. 46—119)

1

This invention relates to dolls, and the main object is the provision of a doll including a body having the legs thereof pivoted to the body and having means for normally urging the doll to move the body thereof from substantially a position of longitudinal alignment with the legs into a position wherein the body is at approximately right angles to the legs.

Another object of the invention is the provision of a doll as above-mentioned, having the feet or legs thereof weighted so that, when the doll is laid on its back in extended position, the said means will cause the body to pivot upward into approximately vertical position while the weighted legs remain in horizontal position.

Owing to the means set forth in the first paragraph above, the normal position of the doll is a sitting-up position. The doll is therefore first straightened out, that is, the body is pivoted into approximate alignment with the legs, this being accomplished by grasping the legs in one hand and the body in the other. A further object of the invention consists in providing additional means, associated with the means mentioned in the said first paragraph, for delaying movement of the body for an interval of time after the doll has been laid on its back, so that when the doll is thus laid on its back it will remain motionless for the said interval of time and then will rapidly assume the sitting position. The said interval of time can be controlled in the manufacture of the doll, as will become apparent below.

The above as well as additional objects will be clarified in the following description, wherein characters of reference refer to like-numbered parts in the accompanying drawing. It is to be noted that the drawing is intended solely for the purpose of illustration, and that it is therefore neither desired nor intended to limit the invention necessarily to any or all of the exact details of construction shown except insofar as they may be deemed essential to the invention.

Referring briefly to the drawing,

Fig. 1 is a side elevational view of the doll of this invention lying on its back in extended position, prior to assuming the sitting-up position, with parts broken away and partly in section, and showing also fragmentarily in broken lines the position some of the parts of the mechanism assumed by the latter when cooing the doll before positioning it as shown in full lines on a table or the like.

Fig. 2 is a view similar to Fig. 1 but showing in full lines the body in raised substantially ver-

tical position and in broken lines the body in the horizontal position shown in Fig. 1.

Fig. 3 is a sectional view taken on the line 3—3 of Fig. 1.

Fig. 4 is an enlarged fragmentary view of a portion of Fig. 3, including the actuating cylinder, with the latter shown in longitudinal section.

Referring in detail to the drawing, the numeral 10 indicates the body of a doll, which is wholly or partly hollow, and the numeral 11 indicates the legs which are weighted in any desired manner as, for example, by means of metallic inserts or fillers 12. It is to be noted that the opposed inner surfaces of the upper ends of the legs 11, shown at 13, are flat and mutually parallel.

The upper portion 14 of the body 10 is wider than the lower portion 15 thereof; in fact, the latter constitutes a reduced extension of the upper portion 14, and its sides 16 are also flat and mutually parallel.

A yoke 17 has two mutually parallel extensions 18 imbedded in the upper ends of the legs 11 and extending from the aligned arms 19, the latter passing through aligned bearings or openings 20 in the body extension 15. A crank 21 extends from the juxtaposed ends of the yoke arms 19 and a sleeve 22, rigid on a piston rod 23, registers rotatably on the shaft-like junction 24 at the extremity of the crank 21, that is, the junction between the opposed arms of the crank 21.

A cylinder 25 has a piston 26, rigid on the rod 23, slidable therein, with a coiled compression spring 27 positioned between the piston 26 and the head end 28 of the cylinder. At a point between the middle of the cylinder and the head end thereof, an opening or vent 29 is provided through the cylinder wall. A longitudinal groove 29a extends along the inside of the cylinder wall between the vent 29 and the head of the cylinder. The opening 25a in the bottom of the cylinder, through which the piston rod 23 passes, is of sufficiently greater area than the cross-sectional area of the rod 23 to permit of free passage of air therethrough in either direction, past the rod 23. An ear 30 extends from the head end of the cylinder and is provided with a bearing opening 31 therethrough.

The body 10 of the doll is formed of two bilaterally symmetrical halves 10a and 10b which are joined along the line 32 in assembling the doll. Near the upper end of the body 10, aligned projections 33, preferably circular in cross-section, extend from the opposed body halves 10a and 10b and meet within the opening 31 of the ear 30. Thus, the combined projections 33 con-

stitute a pivot pin whereby the upper end of the cylinder 25 is pivoted to the upper end of the body 10.

The operation of the doll is as follows. Normally, as above mentioned, the doll assumes the position shown in full lines in Fig. 2. The doll is first "cocked," that is, the body 10 is swung down either into or somewhat beyond a position of alignment with the legs, the last-named position being indicated in broken lines in Fig. 1. Assuming that the body is swung downward, Fig. 1, to assume a position so that it extends downward at a small angle with respect to the horizontal (which it can be made to do if the doll is held in the hands), it is apparent that the piston 26 will have been moved very close to the head end 23 of the cylinder thus compressing the spring 27. During this "cocking" movement of the body, while the piston is moving from the lowermost position shown in Fig. 2 to the position shown in broken lines in Fig. 1, the air between the piston and the head of the cylinder flows out through the vent 29 and air is drawn into the lower portion of the cylinder through the clearance opening 25a. However, when the piston gets beyond the vent 29 in its forward travel, its force tends to compress the air caught between the piston and the head end of the cylinder, except that a leakage escape is provided by the groove 29a and through the vent 29 and opening 25a, thus permitting the piston to travel to a position very close to the head end of the cylinder. However, although the groove 29a has been defined as a groove, it is in fact of very small, almost minute, cross-section, and even a scratch made with a suitable tool such as an awl, on the wall of the cylinder, will suffice as a means of air leakage past the piston. In fact, in case the interior wall of the cylinder is not machined to a good degree of smoothness, sufficient leakage will be provided by the imperfections of the cylinder surface in that air may pass between the piston and the depressions between the raised portions of the unsmoothed surface.

Thus, immediately after "cocking" the doll as aforesaid, when it is placed on its back on a table or the like, the degree of compression remaining in the head of the cylinder will force the piston back a very small distance, sufficient to align the body and legs substantially as shown in full lines in Fig. 1. After being thus placed on its back, the doll will be moved imperceptibly by movement to the left (Fig. 1) of the piston consequent to the very small rate of flow of air past the piston through the groove 29a and out into the lower end of the cylinder or through the vent 29, thus very slowly relieving the compression in the head end of the cylinder. Likewise, the force of the compressed spring 27 is at work, but as it tends to push the piston back its action is resisted by the tendency to create a vacuum at the head of the cylinder and the only air inlet to relieve this vacuum is the groove 29a. As a result of these conditions, the piston will at first move so slowly to the left that its effect on the body 10, that is, pivoting the body 10 upward, is actually imperceptible during this time. However, as soon as the piston has been moved a sufficient distance to the left to begin to clear, and then to clear, the vent 29 so that air can rush through the vent into the head end of the cylinder, the full force of the spring will become effective in moving the piston rapidly to the left so that the body 10 will rapidly swing into the sitting position.

The amount of time after laying the doll flat

on a surface, as shown in Fig. 1, intervening before the doll will visibly pivot into sitting position, is controllable during manufacture in that the vent 29 may be positioned as shown, or more or less distant from the head of the cylinder, as is obvious.

The weighted legs of course prevent the legs from rising and cause the body, instead, to pivot about the axis of connection between the legs and body. Since, during pivoting of the body, the lower end of the body, shown at 33, swings through an arc, to facilitate operation of the doll the lower end 33 of the body is circularly curved with the center of curvature lying in the axis of the yoke arms 19. The rear portion 34 of the lower end 33 of the body is likewise curved along a continuation of the arc of the bottom 33 to provide clearance for the crank 21 and sleeve 22.

Provision of the two halves 10a and 10b joined along the line 32, permits of easy assembling of the complete doll. Provision of the flat surfaces 13 on the legs 11 and the flat surfaces 16 on the body extension 15, permits of the relative rotary movement between the body and the legs with a minimum of resistance and friction.

In case a child wishes to keep the doll in horizontal position, as, for example, lying in bed, the body 10 may be restrained from swinging upward by tucking the bed clothes or covers tightly around the doll.

Instead of utilizing the figure of a doll for the purposes of this invention, any other type or kind of figure may of course be used.

I claim:

1. A figure comprising a hollow body and two legs, a crank shaft having a crank intermediate the length thereof, the ends of said shaft being rigidly secured to said legs thereby pivoting said legs to said body, means connecting said body with said legs for normally urging said body to pivot about said legs from a "cocked" position in which said body and legs are substantially in alignment to a position in which said body lies at a substantially large angle to said legs, said means comprising a cylinder mounted in said body, a piston slidably mounted in said cylinder, a piston rod extending from said piston and having the free end thereof pivoted to said crank, a compression spring mounted in said cylinder between said piston and the head end of the cylinder, said cylinder having a vent through the wall thereof positioned between approximately the middle of the cylinder and the head end thereof, an air escape passage of smaller cross-sectional area than that of said vent for escape of air past said piston, forcible manual alignment of said body with said legs causing said crank to push said piston from a position rearward of said vent to a position near the head end of the cylinder thereby compressing said spring and partly compressing the air in the cylinder between said vent and the head of the cylinder after said piston has passed said vent in moving toward the head of the cylinder and thus forcing said partly compressed air through said escape passage and out through said vent, subsequent release of said figure causing said spring to expand to urge said piston outward from the cylinder, the outward movement of the piston thus resulting being resisted and hence slowed for an interval of time until the piston has moved rearward past said vent owing to the relatively smaller cross-sectional area of said escape passage.

2. The figure set forth in claim 1, said escape passage comprising a longitudinal groove on the inside of the cylinder wall extending toward the head end of the cylinder from said vent.

3. The figure set forth in claim 1, having means for pivoting the upper end of said cylinder in said body, said means comprising a pin inside said body, an ear on said upper end of the cylinder, said ear having an opening therethrough, said pin registering in said opening.
